RAYMOND D. SMITH, OF MILTON, MASSACHUSETTS, ASSIGNOR TO SHAWMUT MACHINE WORKS, INC., OF BOSTON, MASSACHUSETTS, A CORPORATION OF MAINE.

DELAYED CUT-OFF FOR INVERTED GAS-LAMPS.

1,383,575.

Specification of Letters Patent.

Patented July 5, 1921.

Application filed August 7, 1916, Serial No. 113,546. Renewed October 4, 1920. Serial No. 414,650.

To all whom it may concern:

Be it known that I, RAYMOND D. SMITH, a citizen of the United States, residing at Milton, in the county of Norfolk and State of 5 Massachusetts, have invented certain new and useful Improvements in Delayed Cut-Offs for Inverted Gas-Lamps, of which the following is a specification.

My present invention relates to delayed 10 cut-offs for illuminating gas burners of the Bunsen type wherein light is produced by the incandescence of a mantle or non-combustible fabric structure suspended from the lower and open extremity of a downwardly 15 flaming mixing tube for the gas and air of the Bunsen burner, such types of burners being customarily attached to the usual gas bracket or chandelier by means of a "goose neck" extension pipe and, whether or not 20 so attached, being commonly called "inverted" burners.

The object of the invention is to provide in such an inverted, incandescent illuminating gas burner and controlling valve arrangement, manually operable and partially automatic means for actuating the valve, adapted upon suitable actuation thereof, to open the valve for a continuous supply of gas to the incandescent burner, and upon 25 further actuation to tension said valve for automatically delayed burner-extinguishing closure. The time interval before such closure is then controlled by thermostatic means subject to the heat of a normally inactive, auxiliary burner to which gas is 30 supplied by the same actuation that tensions said automatic actuating means. Such auxiliary burner is automatically ignited by a small, constantly burning pilot light (located 35 exterior of the shade holder canopy and substantially higher than the auxiliary burner) and thermally energizes the thermostat, releasing said automatic actuating means and causing thereby a quick and positive 40 closure of the valve and complete extinguishment of both main and auxiliary burners.

The accomplishment of such provision involves the solution of certain specific problems differing materially from those encountered in applying my novel valve-controlling apparatus to other forms of burners, such for instance as that shown in my co-pending application, Serial Number 111,934.

These new problems arise primarily from the new condition (in the form of burner here concerned and above described) that the Bunsen, gas-and-air mixing tube delivers the air and gas mixture downwardly from the point of air inlet thereto, and accordingly must be, or customarily is, offset in relation to the chandelier arm or other supporting bracket. For the same reason the valve control apparatus (preferably together with the before mentioned burner) must also be offset, or positioned beside the mantle burner as a whole, since it obviously cannot be positioned below the Bunsen tube as in the above mentioned application and cannot be superposed relative thereto because of the effect upon the governing thermostat of the intense heat arising from the mantle burner.

An advantageous location for the valve and its automatic governing mechanism is, therefore, at the opposite end of the gas tube, commonly of goose-neck shape, employed to support the entire illuminating burner. When so located, however, there arises the problem of how to provide the necessary operative relation between said auxiliary burner and the main burner so that the former may be automatically ignited at suitable times. The novel means herein provided accomplish this, and for the first time provide broadly for the introduction of a constantly burning pilot flame arranged as a coöperating agent between the main and auxiliary burners and specifically so arranged as to ignite each of these burners independently of the other when gas is supplied thereto. In the disclosures of other arrangements in the applicant's co-pending cases wherein a constantly burning pilot burner has been employed, the same has not been so coöperatively arranged that it alone could directly ignite the auxiliary burner regardless of whether the main burner were operating.

Constantly burning pilot lights have been heretofore used with inverted incandescent gas burners in the form of a small gas conducting tube arranged to tap the main gas supply at a point "back of," or on the supply side of, the local controlling valve. This pilot tube usually extends downwardly and terminates adjacent to the mantle of the main burner and within the chamber formed

by the chimney for said mantle, so that the pilot burner or the main burner can be ignited each from the other, when said other is burning. Such form of pilot light is unsatisfactory for divers reasons, one of these being that, owing to the general lack of rigidity characteristic of such structures, accidental breakage of the mantle (which is very frail and brittle) is a frequent result of attempted installation, adjustment, or even normal operation of the pilot light burner.

Accordingly, a particular object of my present invention is to provide a form of pilot light for an inverted incandescent gas mantle burner which shall be operatively related to the mantle burner to ignite the same but positionally remote from the mantle; and which further, shall be so arranged as to be ignited by the usual operation of igniting the said mantle burner and remain constantly burning independently of the controlling valve for said mantle burner, and to be suitably protected from accidental extinguishment by air drafts.

A further object of my invention is to so locate and construct a partially closed chamber for the pilot light flame and to provide such gas conducting means, leading from the main burner chamber and from the auxiliary heating burner for the thermostat to said partially closed chamber for the pilot flame, that neither the explosive nature of the ignition of either of these two latter burners nor the drafts caused by the heat of said burners when in operation shall be effective to extinguish such pilot light flame.

Other details and specific objects of my invention will appear from the drawings, description and claims hereof.

In the drawings:

Figure 1 is an elevation of the complete burner and controlling valve structure looking at the rear of the valve, the main burner canopy structure being partially broken away or shown in section; Fig. 2 is a detail view of a modified form of certain gas conducting parts near the pilot light housing; Fig. 3 shows another possible and advantageous arrangement of gas conducting parts near the pilot light housing; Fig. 4 is a plan view of the structure shown in Fig. 1 taken in section on the plane 4-4 in that figure; Fig. 5 is an enlarged partial section taken on the plane 5-5 in Fig. 4, showing the arrangement of valve ports and their relative positions during normal operation of the main illuminating burner; Fig. 6 is a section similar to Fig. 5, but showing a different relation of ports; Fig. 7 shows the relation of valve ports when the light has been extinguished; Fig. 8 is a front elevation of the valve controlling mechanism, showing the position of parts after auto-

matic closure of the valve; Fig. 9 is an elevation looking at the left of Fig. 1, with the goose-neck extension pipe and certain other parts broken away; Fig. 10 is a view similar to Fig. 8, but showing the position of the valve controlling mechanism after manual operation of extinguishing means and before automatic closure of the valve or while the thermostat is being heated, and also showing the pilot burner and the upwardly slanting ignition tube for conducting gas from the auxiliary heater burner thereto.

Similar and corresponding parts are indicated throughout the drawings and designated in the following description by the same numerals.

Referring to Fig. 1, particularly, the illuminating mantle appears at 1, and is of the conventional type suspended at its upper and open portion, by means of a flange 2 of refractory material, said flange having the usual inwardly projecting supporting lugs adapted to seat on shelfed recesses in a bracket terminal 3, of the vertical supporting stem and mixing chamber 4 for the gas and air of the main Bunsen burner. At the top of the mixing chamber 4 is shown the usual gas injector and air intake construction wherein adjustment of the gas supply may be had by means of the downwardly pointing needle valve plunger 6 and the conically pointed screw 7, and wherein adjustment of the air openings 8 in the wall of the mixing chamber may be had by rotary adjustment of the circular shield 9 which latter has corresponding openings 10 that may be made to register with the openings 8, such Bunsen gas burner construction being well known in the art.

The combined mantle supporting stem and mixing chamber 4 terminates above the Bunsen gas injector construction in an internally threaded portion 11 and is mounted at this portion upon a goose-neck extension pipe 5. At its other and lower end, this extension pipe is mounted upon a valve block 12, which latter at its bottom, has an internally threaded portion 14, by means of which the entire structure may be mounted upon the usual gas bracket or chandelier.

The mixing chamber 4 is structurally integral with a punched metal dome or canopy structure 13 arranged to receive and hold an outer glass shade 17.

Interior of the chamber formed by said canopy and shade, an inner chimney 16, open at the top, is suspended from a shelf formation of the canopy, and surrounds the mantle.

The valve block contains the usual rotary tapered valve plug 15 whose axis lies transverse of the main gas passage 18, through said block, and which when rotatively actuated by mechanism to be described herein-

after, controls the supply of gas to both the main burner stem 4 and to a small auxiliary Bunsen burner 21 that is located in a bracket extension 22, of the valve block. Adjustment of the supply of gas to the burner 21 may be had by the screw 23.

In another bracket extension 24 of the valve block 12, an upwardly slanting gas port 27 is shown leading from the main gas passage, below the valve plug 15, to the base of an upwardly slanting tube 25 whose top orifice is partially inclosed by a pilot flame protecting cage or lantern chamber 28 fixed to the canopy structure. This cage 15 as shown is cylindrical and has mica covered openings 24 in its wall. Gas supply to the pilot tube may be controlled by the adjusting screw 26. It will be evident that, when ignited, the small flame 29 at the top 20 of the tube (commonly called a pilot light) will remain constantly burning independent of the valve plug 15. This flame is so situated as to ignite the mantle burner whenever gas is supplied to the latter, in a manner which I shall now explain.

Illuminating gas, having a lower specific gravity than air, tends to rise, and therefore upon emission from the lower outlet of the Bunsen mixing chamber 4, and before being ignited, such gas immediately rises to the highest portions of the canopy structure 13. Accordingly it is customary to light this type of illuminating burner at a large opening 40 in the canopy structure, 35 such opening also providing an outlet for the intense heat rising from the mantle burner during its normal operation.

At a high portion of the canopy, therefore, I have provided an opening 41. The canopy shell, about the edges of this opening, extends upwardly for receiving thereupon the bottom, cylindrical portion of a demountable gas ignition hood 42. At the top, this ignition hood is cut and bent to 45 form a curved, inverted trough-shaped extension lying substantially horizontal and partially over the protecting cage for the pilot flame 29, so as to effectively guide and sufficiently direct the out-coming gas toward the pilot flame that such gas may be ignited by said flame. However it should be noted that the hood 42 forms very little inclosure of the gas in the neighborhood of the pilot flame, and that the horizontal terminal of 55 this hood is acutely beveled and otherwise shaped to purposely prevent such inclosure and to allow unconstricted communication with, and access of free air at the place of ignition. The ignition of the considerable 60 volume of gas that has issued from the main burner after opening the valve, is practically instantaneous throughout, and therefore of an explosive nature. Such explosive effect 65 would be sufficient to extinguish the pilot flame, were the latter directly in line with

the outlet orifice of the delivery hood, or if both said pilot flame and orifice were inclosed within a chamber providing little communication with the outside air. I have also shown a shield 43, in Figs. 1 and 4, 70 which, together with the walls of the canopy, forms, in effect, an inverted funnel arranged to collect the gas rising from the main burner and to deliver the same through the ignition hood 42 more efficiently than 75 would be possible without such shield.

This pilot-light, gas igniting arrangement does not necessitate a separate or unusual operation for igniting the pilot burner, when for any reason the latter has become 80 extinguished, since such ignition of the pilot burner is automatic and occurs upon ignition of the main mantle burner at the opening 40 in the usual manner. The cause of such automatic ignition of the pilot burner 85 lies also in the nature of the ignition and inflammation occurring throughout the volume of gas which has collected before applying the match or other igniter. Such volume of gas extends to and includes that 90 gas escaping from the pilot burner so that the latter is ignited simultaneously with the main mantle burner.

In Fig. 2, I have shown an auxiliary and smaller, inverted, trough-shaped extension 95 44 contained within and fixed to the delivery hood. Without making the pilot flame 29 more susceptible to the explosive disturbance of the gas ignition, such auxiliary extension may cause more immediate and reliable delivery of the rising gas to such pilot flame and thereby quicker ignition of the main burner when gas is supplied thereto.

Fig. 3 shows another possible means for obtaining quicker ignition of the main 105 burner if desired. A small gas conducting tube 45 is shown, terminating adjacent to the orifice of the pilot light burner and extending downwardly into the canopy chamber where it spreads into a collecting shield 110 for the rising gas. A short path for the gas from the canopy chamber to the pilot flame 29 is thereby afforded and such gas issuing from said tube will burn, thus increasing the size of the pilot flame 29 and 115 causing more ready ignition of the gas delivered through the ignition hood 42.

Referring particularly to Figs. 4, 8, and 10, I shall now describe the mechanism by which the movement of the valve plug 15 is 120 controlled. Manual control of this mechanism is afforded by the chains 65 and 68. A downward pull on chain 68 in Fig. 8 first swings the spring actuated latch lever 66 to the broken line position thus disengaging it from the locking projection 78 of the vertical, circular supporting plate 31, which supporting plate is fixed to the valve block 12. The latch lever is pivoted to one 125 end of the double-ended control lever 35 130

which is loosely and pivotally mounted on a stem extension 30 of the valve plug 15 and its other end carries the chain 65. Further pull on the chain 68 will therefore 5 swing the control lever 35 to its position indicated by broken lines in Fig. 8, where it will be stopped by engagement with another projection 54 of the supporting plate 31. During this movement, the valve plug 10 has been positively rotated a corresponding amount by engagement of the control lever 35 with a rearwardly bent extension 37 of the dog member 36, the latter being fast to the end of the valve stem 30 and normally 15 maintained in such engagement with the control lever 35 by a spring 38. Control chain 65 may now be pulled downwardly which will swing the control lever 35 in the reverse direction until the spring latch 20 lever 66 automatically locks it in the position shown in Figs. 7 and 8. But from Fig. 10 it will be seen that during this latter movement, the dog member 36 has been intercepted in an intermediate position and 25 that it is held in this position against the tension of spring 38 by a spur shaped projection 52 carried fast to the inner surface of the curved bi-metallic thermostat 53.

The thermostat 53 is mounted at one end 30 to the projection 54 of the supporting plate 31 and is clamped thereto in surface contact with the base of an upwardly extending heater member 56 by screws 55, 55. The heater member 56 terminates in a hollow 35 hooded portion 57 that is perforated at its top and is positioned directly over the auxiliary burner 21.

Directly above this hooded terminal of 40 the heater member, is the lower end of an ignition chimney tube 32 which tube slants upwardly and is entirely open at both ends. This ignition tube is fixed to the outer canopy shell and its higher end falls directly beneath and slightly below the open bottom 45 of the pilot flame protecting cage. The lower end of the tube encompasses the perforated top of the heater hood, but leaves a free passage for air into said tube around the exterior of the hood. Gas, rising from 50 the auxiliary burner 21 and through the opening in the top of the heater hood, is guided upwardly through the chimney tube 32 into the pilot light cage, and upon igniting from the pilot flame, flares back through 55 said tube, subsequently burning with a blue flame at the top of the burner 21 only, and under the hood 57 as shown in Fig. 10.

A loose, stationary roller is mounted on a 60 stud projecting from the support plate 31 and engages the inner surface of the thermostat to help the thermostat bear the load of the tensioned dog member 36. This dog member engages the thermostat spur 52 by means of a spring actuated latch 46 pivoted 65 to the dog member at 47 and capable of

yielding in one direction only, namely counter-clockwise in Fig. 7, or when passing the spur 52 by clockwise rotation of the dog member 36. A casing 33 is provided for the valve mechanism. 70

Having thus described the controlling mechanism I shall now explain the operation of the complete burner and valve arrangement, after which I shall point out what constitutes the novel features of my invention in the appended claims. 75

Starting from the position of parts as shown by broken lines in Fig. 8, where the valve ports are related as in Fig. 5 and where the main mantle burner is lighted and 80 adapted for continuous operation, when it be desired to extinguish the light, control chain 68 is pulled downwardly which moves the parts to the position indicated in Fig. 10, where the valve ports are related as 85 shown in Fig. 6. It will be seen that the small port 19 in the valve plug now registers with the corresponding port 20 leading to the auxiliary burner 21 in the valve block and that gas is thereby supplied which is then 90 ignited from the pilot flame 29, as heretofore explained, the supply of gas to the main mantle burner having been substantially unaltered by movement of the valve plug. The flame of the auxiliary burner now plays 95 against the hooded terminal 57 of the heater member 56 as shown in Fig. 8, which latter member conducts heat from said flame to the thermostat. The thermostat upon being 100 thus heated, straightens, or bends generally outwardly, assuming the broken line position indicated in Fig. 10 after a certain 105 time interval, whereupon the spur 52 releases the dog member 36 and the latter is immediately impelled by the spring 38 to 110 the position as shown in Fig. 8, where the relation of valve ports is as shown in Fig. 7, and all gas supply to both the auxiliary heater burner and to the main mantle burner has been cut off. The pilot flame 29, however, remains burning and when gas is again 115 supplied to the main mantle burner, ignites the latter as heretofore explained.

The valve may be opened again at will for supplying gas to the main mantle burner 115 by pulling downwardly on chain 68. This restores the valve plug to the position shown in Fig. 5 as before explained. It should be noted that in this position, no gas is supplied to the auxiliary burner 21 and that 120 the main mantle is adapted to remain in operation for an indefinite period of time.

Other variations of the precise illustrated or described embodiment of my invention will be readily apparent to those skilled 125 in the art;—and without therefore limiting myself to that embodiment, what I claim as my invention is:—

1. The combination, in an inverted mantle gas lamp, having a gas conductive goose 130

neck connecting the same with a laterally located fuel control valve and embodying a downwardly directive Bunsen tube for the gas and air mixture arranged with an air 5 inlet near the top thereof and an outlet for the fuel mixture at its bottom end whereat is suspended the illuminating mantle,—of an auxiliary burner at the valve end of said goose neck connected to be also governed as 10 to fuel supply by said valve and constituting part of automatic agencies for controlling closure thereof; a pilot burner constantly supplied with gas independently of said valve, positioned intermediate said Bunsen 15 tube outlet and said auxiliary burner and at a higher level than either; and separate means for collecting gas issuing respectively from the said Bunsen tube outlet and from said auxiliary burner; said means being arranged 20 to direct said gas into common proximity to the flame of the pilot burner, so that either said mantle burner or said auxiliary burner when supplied with gas is ignitable independently of the other directly 25 by said flame.

2. An inverted mantle gas burner arrangement having a mixing chamber for the gas and air of the mantle burner with a fuel outlet at the lower end thereof coöperating 30 with the suspended illuminating mantle, and including in combination, a valve controlling the supply of gas to said mixing chamber; a normally inoperative, auxiliary, heating burner; a pilot burner positioned to ignite 35 both said mantle burner and said auxiliary burner and arranged to be constantly supplied with gas independent of said valve; manually operable, automatically acting mechanism, operatively related to said valve 40 and arranged to govern the flow of gas to said auxiliary burner, said mechanism including a controlling thermostat adapted to be subjected to the heat from said auxiliary burner and thereby to be made operative to 45 cause a movement of said valve.

3. An inverted mantle gas burner arrangement, having a mixing chamber for the gas and air of the mantle burner with a fuel outlet in the lower end thereof coöperating with 50 the suspended illuminating mantle; and including, in combination, a valve controlling the supply of gas to said mixing chamber; a normally inoperative, auxiliary heating burner; a pilot burner partially inclosed by 55 a protecting cage, and arranged to be constantly supplied with gas independent of said valve; gas conducting means arranged to deliver gas from the mantle burner into igniting relation with said pilot burner; gas 60 conducting means for delivering gas from said auxiliary burner into igniting relation with said pilot burner; and manually operable, automatically acting means operatively related to said valve, and arranged to govern 65 the flow of gas to said auxiliary burner, said

means including a controlling thermostat adapted to be subjected to the heat from said auxiliary burner and thereby made operative to cause a movement of said valve.

4. An inverted mantle gas burner arrangement, having a mixing chamber for the gas and air of the mantle burner with a fuel outlet at the lower end thereof coöperating with the suspended illuminating mantle; and including, in combination, a valve controlling 70 the supply of gas to said mixing chamber; a normally inoperative, auxiliary, heating burner; a pilot burner partially inclosed by a protecting cage, and arranged to be constantly supplied with gas independent of 80 said valve; gas conducting means arranged to deliver gas from the mantle burner into igniting relation with said pilot burner; gas conducting means for delivering gas from said auxiliary burner into igniting relation 85 with said pilot burner; and manually operable, automatically acting means operatively related to said valve, and arranged to govern the flow of gas to said auxiliary burner, said means including a controlling thermo- 90 stat and a heat receiving and conducting member extending from said thermostat to the flame of the auxiliary burner, whereby the thermostat may be thermally energized and thereby made operative to cause a movement of said valve.

5. An inverted mantle gas burner arrangement embodying, in combination; a mixing chamber for the gas and air of the mantle burner mounted at one end of a gas conducting, gooseneck, extension pipe, said mixing chamber having a fuel outlet at its lower end coöperating with the suspended illuminating mantle; a valve at the other end of said extension pipe adapted to control 100 the supply of gas to the mantle burner; a normally inactive, auxiliary, heating burner structurally associated with said valve; a pilot burner operatively associated with said mantle burner and with said auxiliary 110 burner, positioned substantially higher than the fuel outlets in both of said burners, and arranged to be constantly supplied with gas independent of said valve, and manually operable, automatically acting mechanism, operatively related to said valve and arranged 115 to govern the flow of gas to said auxiliary burner, said mechanism including a controlling thermostat adapted to be subjected to the heat from said auxiliary burner thereby to be made operative to cause a movement of said valve.

6. An inverted mantle gas burner arrangement embodying, in combination; a mixing chamber for the gas and air of the mantle 125 burner mounted at one end of a gas conducting, gooseneck, extension pipe, said mixing chamber having a fuel outlet at its lower end coöperating with the suspended illuminating mantle; a valve at the other end of said ex- 130

6 tension pipe adapted to control the supply of gas to the mantle burner; a normally inactive, auxiliary, heating burner structurally associated with said valve; a pilot burner 5 partially inclosed by a protecting cage, and arranged to be constantly supplied with gas independent of said valve; gas conducting means arranged to guide unburned gas, issuing from said mantle burner, into igniting relation with the heat from said pilot burner; gas conducting means arranged to guide unburned gas issuing from said auxiliary burner into igniting relation with the heat from said pilot burner; and manually 10 operable automatically acting mechanism, operatively related to said valve and arranged to govern the flow of gas to said auxiliary burner, said mechanism including a controlling thermostat adapted to be subjected to the heat from said auxiliary burner thereby to be made operative to cause a movement of said valve.

7. An inverted gas mantle arrangement embodying in combination; a mixing chamber for the gas and air of the mantle burner mounted at one end of a gas conducting, gooseneck, extension pipe, said mixing chamber having a fuel outlet at its lower end cooperating with the suspended illuminating 15 mantle, both said outlet and said mantle being contained within a canopy-covered chamber having openings in its upper portion for the escape of heat; a pilot burner encompassed by a protecting cage having openings at the top and bottom thereof and arranged to be constantly supplied with gas independent of said valve, a gas delivery hood coöperating with an opening in said canopy to deliver unburned gas therefrom 20 in proximity to said cage in the presence of free air and into igniting relation with the heat from said pilot burner; a gas conducting tube arranged to receive unburned gas issuing from said auxiliary burner and to 25 deliver the same in proximity to said cage in the presence of free air and into igniting relation with the heat from said pilot burner; and manually operable, automatically acting mechanism, operatively related 30 to said valve and arranged to govern the flow of gas to said auxiliary burner,—said mechanism including a controlling thermostat adapted to be subjected to the heat from said auxiliary burner, thereby to be made operative to cause a movement of said valve.

8. An inverted gas mantle arrangement embodying in combination; a mixing chamber for the gas and air of the mantle burner suspended at one end of a gas conducting, gooseneck, extension pipe, said mixing chamber having a fuel outlet at its lower end cooperating with the illuminating mantle, both said outlet and said mantle being contained within a canopy covered chamber having 35 openings in its upper portion for the escape of heat; a pilot burner encompassed by a protecting cage having openings at the top and bottom thereof and arranged to be constantly supplied with gas independent of said valve, a gas delivery hood coöperating with an opening in said canopy to deliver unburned gas therefrom 40 in proximity to said cage in the presence of free air and into igniting relation with the heat from said pilot burner; a gas conducting tube arranged to receive unburned gas issuing from said auxiliary burner and to 45 deliver the same in proximity to said cage in the presence of free air and into igniting relation with the heat from said pilot burner; and manually operable, automatically acting mechanism, operatively related 50 to said valve and arranged to govern the flow of gas to said auxiliary burner,—said mechanism including a controlling thermostat adapted to be subjected to the heat from said auxiliary burner, thereby to be made operative to cause a movement of said valve.

9. An inverted gas mantle arrangement embodying in combination a mixing chamber for the gas and air of the mantle burner suspended at one end of a gas conducting, gooseneck, extension pipe, said mixing chamber having a fuel outlet at its lower end cooperating with the illuminating mantle, both said outlet and said mantle being contained within a canopy covered chamber having 55 openings in its upper portion for the escape of heat; a pilot burner encompassed by a protecting cage having openings at the top and bottom thereof, and arranged to be constantly supplied with gas independent of said valve; a gas delivery hood coöperating with an opening in said canopy; and an expanded hood-like extension communicating with said opening, extending downwardly 60 interior of said canopy covered chamber and arranged to collect unburned gas rising from the mantle burner and discharge same through said delivery hood directly over said cage in the presence of free air and into igniting relation with the heat from said pilot burner; a gas conduit arranged to receive unburned gas from said auxiliary burner and to 65 deliver the same directly under said cage in the presence of free air and into igniting relation with the heat from said pilot burner; and manually operable automatically acting mechanism operatively related to a valve for the main and auxiliary burners, said mechanism including a controlling thermostat adapted to be subjected to the 70

ing openings in its upper portion for the escape of heat; a pilot burner encompassed by a protecting cage having openings at the top and bottom thereof and arranged to be constantly supplied with gas independent of said valve, a gas delivery hood coöperating with an opening in said canopy to deliver unburned gas therefrom in proximity to said cage in the presence of free air and into igniting relation with the heat from said pilot burner; a gas conducting tube arranged 75 to receive unburned gas issuing from said auxiliary burner and to deliver same in proximity to said cage in the presence of free air and into igniting relation with the heat from said pilot burner; and manually operable, automatically acting mechanism, operatively related to said valve and arranged to govern the flow of gas to said auxiliary burner, said mechanism including a controlling thermostat and a heat receiving and conducting member extending from said thermostat and terminating in a hollow, hood-shaped portion, perforated at the top, and positioned directly over said auxiliary burner and directly beneath the lower end of said gas conducting tube for the gas from said auxiliary burner, whereby the thermostat may be thermally energized and thereby made operative to cause a movement of said valve.

9. An inverted gas mantle arrangement embodying in combination a mixing chamber for the gas and air of the mantle burner suspended at one end of a gas conducting, gooseneck, extension pipe, said mixing chamber having a fuel outlet at its lower end cooperating with the illuminating mantle, both said outlet and said mantle being contained within a canopy covered chamber having 90 openings in its upper portion for the escape of heat; a pilot burner encompassed by a protecting cage having openings at the top and bottom thereof, and arranged to be constantly supplied with gas independent of said valve; a gas delivery hood coöperating with an opening in said canopy; and an expanded hood-like extension communicating with said opening, extending downwardly 95 interior of said canopy covered chamber and arranged to collect unburned gas rising from the mantle burner and discharge same through said delivery hood directly over said cage in the presence of free air and into igniting relation with the heat from said pilot burner; a gas conduit arranged to receive unburned gas from said auxiliary burner and to 100 deliver the same directly under said cage in the presence of free air and into igniting relation with the heat from said pilot burner; and manually operable automatically acting mechanism operatively related to a valve for the main and auxiliary burners, said mechanism including a controlling thermostat adapted to be subjected to the 105

110

115

120

125

heat from said auxiliary burner and thereby to be made operative to cause a movement of said valve.

10. In a Bunsen gas burner arrangement embodying a main burner mixing tube for the gas and air with the fuel inlet at the upper end thereof and a burner outlet for the fuel therebelow, together with a valve controlling the supply of gas to said mixing tube, and positionally remote therefrom, in combination; automatic, thermostatically controlled means operatively related to said valve, comprising a normally inactive auxiliary heating burner with a gas supply therefor, independently governable by a partial movement of said valve, and a controlling thermostat, adapted to be subjected to the heat of said auxiliary burner and thereby to be made operative to cause a movement of said valve; and a pilot burner arranged to be constantly supplied with gas independent of said valve, so co-operatively positioned relative to the said auxiliary burner that the pilot burner is rendered directly operative to ignite the auxiliary burner independently of main burner operation.

11. In a Bunsen gas burner arrangement embodying a main burner mixing tube for the gas and air with the fuel inlet at the upper end thereof and a burner outlet for the fuel therebelow, together with a valve controlling the supply of gas to said mixing tube and positionally remote therefrom, in combination; automatic, thermostatically controlled means operatively related to said valve comprising, an auxiliary heating burner with a gas supply therefor governed by said valve; and a controlling thermostat, together with a heat conducting member extending from the latter and terminating over said auxiliary burner in a hollow, hood-shaped portion perforated at the top, and adapted to be heated by the flame of such auxiliary burner and to conduct such heat to the thermostat whereby the latter shall be made operative to cause a movement of said valve; and a pilot burner arranged to

be constantly supplied with gas independently of said valve, and so co-operatively positioned relative to the said auxiliary burner that automatic ignition of the latter may be caused by said pilot burner.

12. A pilot light arrangement for inverted mantle gas lamps embodying in combination with the downwardly flaming main burner and mantle suspended therebelow, a canopy constituting the upper covering of the main burner combustion chamber; a pilot burner adjacently exterior of said canopy; and gas directive means disposed upwardly from an opening in a high portion of said canopy, including a horizontally disposed hood extending laterally from above said opening to a point proximate and above the flame of said pilot burner thereby to check the upward stream of gas issuing from said canopy through said opening and cause the same to be diffused proximate the flame of said pilot burner.

13. A pilot light arrangement for inverted mantle gas lamps embodying in combination with the downwardly flaming main burner and mantle suspended therebelow, a canopy constituting the upper covering of the main burner combustion chamber; a pilot burner adjacently exterior of said canopy; and gas directive means disposed upwardly from an opening in a high portion of said canopy, including a horizontally disposed hood extending laterally from above said opening to a point proximate and above the flame of said pilot burner thereby to check the upward stream of gas issuing from said canopy through said opening and cause the same to be diffused proximate the flame of said pilot burner.

Signed in Boston, Massachusetts, this 5th day of August, 1916.

RAYMOND D. SMITH.
